UNITED STATES PATENT OFFICE.

GEORGE A. HILLER, OF EAST ROCHESTER, NEW YORK.

ELEVATOR.

Application filed April 9, 1921. Serial No. 460,011.

To all whom it may concern:

Be it known that I, GEORGE A. HILLER, a citizen of the United States, residing at East Rochester, in the county of Monroe and

5 State of New York, have invented certain new and useful Improvements in Elevators, of which the following is a specification.

The object of this invention is to provide a new and improved form of movable elevating mechanism which is especially adapted for use in the construction of concrete walls for dwelling houses, building foundations, retaining walls in fact for all concrete construction work in which the concrete must be poured from an elevation in order to secure proper distribution of the concrete in the forms with a minimum amount of labor.

Another object of this invention is to provide the elevating mechanism with means whereby not only the concrete can be handled most efficiently, but also the sections of the forms into which the concrete is to be poured.

25 In the accompanying drawing:

Figure 1 is a front elevation of the elevating mechanism with the uprights partly broken away.

Figure 2 is a side elevation of the elevating mechanism with the uprights partly broken away.

Figure 3 is a detail sectional view of one of the guides for the elevating tipple, the section being taken on the line 3^x—3^x of 35 Figure 2.

Figure 4 is a vertical sectional view of the upper end of the elevating mechanism, the section being taken on the line 4^x—4^x of Figure 1.

40 Figure 5 is a detail perspective view of the elevating tipple and a portion of the guides between which the tipple is mounted to slide.

Figure 6 is a detail sectional view thru 45 the anchor by means of which the upright guides are elevated, the section being taken on the line 6^x—6^x of Figures 2 and 3.

In the several figures of the drawing like reference numerals indicate like parts.

50 Concrete elevators are used to elevate the mixed concrete to a predetermined height alongside the form or mold of the structure to be filled therewith. This height must be greater than the height of the forms into

55 which the concrete is to be poured, in order that the chute for distributing the elevated

concrete can be held at an inclination sufficient to allow the concrete to flow from the top of the elevator to the desired point in the mold by force of gravity.

60 The elevator forming the subject matter of my present invention is preferably built on a base made up in this instance of two pairs of cross beams 1, 1 and 2, 2; one pair being mounted on top of the other and at right angles thereto. On the under side of the beams 2, 2 are provided the bearings 4 in which the shafts 5 and 6 are mounted to rotate. The shafts in turn carry on their outer ends the wheels 7, 8, 9 and 10 which are adapted to support the base of the elevator, and also make it movable for the purpose of changing the location of the elevator.

65 Suitably fastened to each of the beams 1, 1 and facing each other are a pair of uprights 11 and 12. These uprights are each formed by two angle irons and are riveted to the inner side of each of the beams 1, 1. Each pair of angle irons is supported by 70 one of the beams 1 and the members being properly spaced apart at suitable intervals by means of the spacing bars 13 on the outside of the angle irons and with the cross beams 14 and 15 at the top thereof. The cross beams 14 and 15 in turn are spaced apart by a pair of spacing members 16 and 17, one at each end of the cross bars 14 and 15. An open or rectangular frame is thus formed at the top of the uprights 11 and 12 which holds these uprights properly 75 spaced apart from one another, corresponding to the spacing of these same parts at the point where they are mounted to the cross bars 1 of the base.

80 Mounted to telescope in each of the pairs of uprights 11 and 12 is a second pair of uprights 18 and 19. Each of the members of this second pair of uprights is preferably made up of an angle iron of somewhat smaller dimensions than the angle irons forming the first pair of uprights. A third pair of uprights 20 and 21 preferably similarly constructed may be mounted to telescope in the second pair of uprights. This 85 third pair of uprights carries a head, at the top of which the pulley 23 is mounted.

90 The head may be made up of a pair of I beams 24 and 25, which in turn are mounted on top of the overhanging arms 26 and 27. The arms 26 and 27 are fastened to the 95 outside of each of the uprights 20 and 21

respectively and the I beams 24 and 25 rest on top of them and span the distance between the uprights 20 and 21 at their upper extreme ends. Mounted between the beams 24 and 25 in suitable bearings supported thereon is the pulley 23 over which the hoisting cable 30 is adapted to travel.

One end of this hoisting cable is preferably permanently attached to the beams 24 and 25 and passes from this point down around the pulley 31, carried between the cross beams 32 and 33 of the tipple carrier or frame. From the pulley 31 the cable passes around the pulley 23, as above pointed out, and thence over the pulley 35 and down on the outside of the uprights to a pulley 36 that is supported on brackets mounted near the base of the elevator. From there the cable is passed over a horizontally pivoted pulley 37 to a winding or hoisting drum (not shown) by means of which the cable is pulled or released in order to raise or lower the tipple of the elevator.

The frame or carrier that carries the tipple comprises preferably the angle irons 38, 39, 40 and 41, forming guides which are adapted to slide on the outside of the uprights forming the guides therefor. At the top the angle irons are spaced apart in pairs by means of the angle irons 42 and 43, and similar angle irons are provided at the bottom to properly space the angle irons of the frame apart so as to make it slide on the inside between the pair of uprights previously described. The angle irons 38 to 41 inclusive are held against the inside of the uprights by means of the pair of cross beams 32 and 33 which are attached to the spacing angles 42 and 43 at the top of the frame. A similar pair of angles is provided at the bottom of the frame to bind the spacing member of the frame together. Mounted between the angles forming the spacing members at the lower end of the tipple frame is the rock shaft 46, on which the tipple 47 proper is supported. This tipple comprises the frame 48 which tapers toward the bottom thereof and between which the concrete container 49 is carried. The concrete container is carried above the rock shaft 46 in order to make the same top heavy for a purpose that will presently appear. The container is also mounted so as to be overbalanced to the front thereof to insure the tipping of the tipple in the desired direction.

On the side of each pair of angle irons 38, 41 forming part of the tipple carrier are mounted the dogs 50 and 51. These dogs are adapted to engage with their front ends into suitable slots 52 and 53 in the top edge of the container 49. This engagement of the dogs with the container normally holds the container from tipping forwardly while the

container is being filled and raised. When the tipple carrier is elevated by the hoisting mechanism in the manner above described the dogs 50 and 51 are brought into contact with the cam bars 54 carried on the outside of the upper set of uprights. On the further movement the dogs are forced to ride up on the inside of the cam bars 54 and in so doing are forced to tilt into the dotted line position indicated in Figure 5. This in turn moves the forward end of the dogs out of engagement with the slots 52 and 53, which releases the tipple and allows it to tilt forward.

At the point where the tipple is tilted in this manner the tipple has just passed the hopper 55, carried on the upper set of uprights. The forward end of the tipple then rests on the inner edge of the hopper while the tipple carrier is still further elevated until the container has reached the position shown in Figure 4 in which it is almost perpendicular to the upright of the elevator. The contents of the container begin to slide into the hopper as soon as the tipple tilts and makes contact with the hopper 55, but the tipple is not emptied until it has been elevated into the position shown in Figure 4.

The bottom of the tipple is carried above the pivot around which it rocks. This makes the tipple top heavy so that as soon as the tipple is released by the dogs the tipple begins to tilt. The shallow curved bottom of the container is provided so that the concrete contained therein will easily slide out therefrom and empty into the hopper 55. The curvature of the bottom is made in such a way so that the container has a continuous bottom without sharp bends and curvatures therein and this insures a quick release of the concrete contained therein.

Mounted at the top of the last pair of uprights and supported by the I beams 24 and 25 is a boom 56. This boom is supported at its outer end by the triangular frame work on the bottom of which is carried the hopper 55. The triangular frame in turn is supported by the arms 26 and 27 at the top and the braces 57 near the bottom thereof. Both the arms 26 and 27 and the braces 57 project out from the uppermost pair of uprights, with which they form a unit.

On the outer end of the boom 56 is mounted a pair of tackles 58 and 58^A. One of these tackles is used for the purpose of hoisting and placing the discharge end of the distributing trough 59, to which it is fastened with the one end thereof. The other of the tackles is used for the purpose of hoisting and handling the sections of the forms of the mould into which the concrete is to be poured. The receiving end of the distributing trough is anchored to the hopper 55 by means of the chain 55^A, which is

suspended from the cross bar 55^B of the triangular frame. This chain holds the end of the chute against the exit of the hopper, and the engagement of the trough with the hopper permits the trough to be wrung sideways at any horizontal angle in front of the elevating mechanism, and the tackle is adapted to hold the trough at the desired vertical angle or place it on the form by which in 10 turn it is supported.

The elevation to which the concrete is raised, for the purpose of distributing the concrete and filling the mold therewith is governed by the position of the uppermost 15 pair of uprights. These uprights carry the hopper 55, boom 56 and the tilting mechanism which automatically releases the tipple so that it dumps its contents into the hopper.

20 The upper uprights 20 and 21, as well as the intermediate uprights 18 and 19, telescope in the first and second pair of uprights respectively, as heretofore pointed out. This makes it possible to raise the second pair of 25 uprights with relation to the first pair of uprights, and the third pair of uprights with relation to the first and second pair of uprights. To do this a winch 60 is mounted on the braces that support the first pair of uprights. This winch is operated by the crank 61 and rotates the drums 62 and 63. The cables 64 and 65, of each of which one end is fastened to its corresponding drum, are passed over the pulleys 66 and 67 at each side 30 of the top of the first pair of uprights, which guide the cable down between the first pair of uprights. A hook 68 is fastened to the end of each of the cables 64 and 65. These hooks are adapted to engage the under side 35 of suitable connecting links 69 which bridge each pair of uprights near the bottom thereof.

A connecting link 69 is provided for each 40 pair of angle bars of the second and third pair of uprights and when it is desired to elevate the second pair of uprights the hooks 68 are hooked under the connecting link of this pair of uprights. On the operation of the winch 60 the cables 64 and 65 are wound up 45 on the drums 62 and 63 respectively and in so doing pull the hooks on the ends of the cable up between the first pair of uprights. The pair of uprights to which the hooks are attached are thus raised and the upper portion 50 thereof moves out between the preceding set of uprights. After the desired elevation has been reached suitable bolts are passed through the holes 71 provided in the sides 55 of each of the uprights. When the bolts are passed through the holes 71 in the first pair 60 of uprights into the holes 71 in the second pair of uprights, with which they register, the second pair of uprights is held in the elevation to which it has been raised by the 65 winch on the first pair of uprights. In the

same manner the third pair of uprights can be elevated and supported on the second pair of uprights.

In this way any desired elevation of the hopper 55 can be secured in order to raise 70 the concrete to the proper level for distribution into the forms.

It will be noted that each upright is, in this instance, formed of two angle irons, one flange of each angle iron lying in a plane 75 with the flange of the other angle iron and the other two flanges being parallel and on the outer sides of the upright, thus, in effect, providing a channel between the flanges in which another upright may operate and may be housed, as will be seen by referring more particularly to Fig. 3. The frame or carrier on which the container is mounted operates between two of the uprights and has at opposite sides a pair of angle irons, the members of each of these pairs having each a flange in a plane with the flange on the other member, and a flange parallel with the flange on the other member, the parallel flange forming a channel between them in which is 80 received one of the uprights. The opposite ends of each of these angle irons are split and deflected away from these uprights. This arrangement, as a whole, permits the carrier to move from one upright to another while 85 being held to its guiding upright.

While the invention has been described and more particularly with reference to elevators used for concrete work, it is apparent that the invention is not limited to this use and 100 that certain features are capable of use in elevators of any type.

I claim:

1. In an elevator, the combination with uprights arranged in telescoping relation in 105 a plurality of different sets each set having a guiding surface, of a distributing means mounted on the uppermost set of uprights to move therewith, a frame guided on the guiding surfaces of the different sets, and a container mounted to move on the frame to discharge the contents thereof to the distributing means.

2. In an elevator, the combination with a plurality of telescoping uprights arranged in 110 different sets each set having a guiding surface, of a distributing means mounted on the uppermost uprights of the different sets, a frame guided on the guiding surfaces of the uprights of the different sets, a container 115 mounted to move on the frame, means carried by the uppermost uprights for effecting the movement of the container on the frame to cause the contents of the container to be discharged to the distributing means, and means for elevating the frame on the uprights into cooperation with said last mentioned means to cause the container to discharge its contents to the distributing means.

3. In an elevator, the combination with a 120

plurality of telescoping uprights each having a guiding surface, of distributing means carried by the uppermost one of said uprights and moving therewith, and a dumping container guided by the guiding surfaces of the different uprights toward and from the distributing means.

4. In an elevator, the combination with a plurality of telescoping uprights each formed with a guiding surface, of a base to which one of said uprights is rigidly secured, distributing means mounted on one of the other uprights, so as to be adjusted with reference to the base, and a dumping container guided by the guiding surfaces on the different uprights and adapted to discharge its contents into said distributing means.

5. An elevator comprising a portable base, a pair of uprights rising from the base and formed with guiding surfaces, an open frame connecting the uprights, connected uprights guided on the first named uprights and formed with guiding surfaces, a frame guided on the guiding surfaces of all of said uprights through said open frame, a container mounted to move on said frame, and hoisting mechanism connected with the last mentioned frame and with the movably connected uprights.

6. An elevator comprising a portable base, uprights rising from said base and formed with guiding surfaces, an open frame connecting the upper ends of said uprights, upper uprights adjustable vertically on the first mentioned uprights and formed with guiding surfaces, a frame guided on the guiding surfaces of the lower and the upper uprights through said open frame, and a container movably mounted on said last mentioned frame.

7. An elevator comprising a plurality of uprights, each formed of a pair of angle irons, spaced apart, the angle irons of each pair having each a flange in the plane of the flange of the other member of the pair and having the other flange parallel with the other flange of the pair and on the outer sides of the upright to form a channel between them, other uprights guided in the channel formed between the two parallel flanges of the first named uprights, a connection between the upper ends of the last mentioned uprights, a movable carrier guided on all the uprights, and means for moving the carrier connected with the latter and with the connection between the upper uprights.

8. An elevator comprising two uprights having channels on their opposed faces, two other uprights received within and guided in said channel, a connection between the upper ends of the second mentioned uprights, a carrier guided on both pair of uprights, and hoisting mechanism connected with said

carrier and with the second mentioned pair of uprights.

9. An elevator comprising a plurality of pairs of uprights, each pair having channels in the opposed faces of its members and the channel of each upright receiving an upright of another pair and acting as a guide for said upright, and a carrier guided on all the uprights.

10. An elevator comprising a portable base having a pair of uprights rigidly secured thereto and formed with guiding surfaces, another pair of connected uprights vertically adjustable on the first mentioned uprights and formed with guiding surfaces, and a carrier having guides at opposite sides guided on the guiding surfaces of both pair of uprights.

11. An elevator comprising a pair of uprights each formed of two angle irons, each with a flange thereof in a plane with the flange of the other angle iron and each having the other flange parallel with the other flange of the other angle iron, and the outer sides of the upright, a carrier frame having two angle irons on opposite sides each with a flange thereof in a plane with a flange on the other angle iron and the other flange parallel with the other flange of the other angle iron, the last named flanges receiving between them the parallel flanges of one of the first named uprights, and a pair of uprights with the members thereof arranged on opposite sides of the carrier frame, each between the two parallel flanges of one of the uprights, and hoisting mechanism connecting the carrier frame with the last mentioned pair of uprights.

12. An elevator comprising two uprights having channels in their opposed faces, a pair of uprights movable in said channels, and a carrier frame arranged to cooperate with the outer faces of both of said uprights.

13. An elevator comprising a pair of uprights provided with channels in their opposed faces, two uprights mounted to move in said channels, and a carrier frame having a pair of angle irons on two opposite sides thereof, said angle irons on each side having a flange of each member parallel with the flange of the other, and said two uprights receiving between them the two uprights on said side of the carrier.

14. An elevator comprising a plurality of pairs of uprights, a member of each pair telescoping with a member of another pair, and a carrier mounted to move between the uprights and having guides on opposite sides arranged to travel on all of said uprights.

15. In an elevator the combination of a series of telescoping uprights, a frame mounted to slide on said uprights, a second frame mounted to rock within said first

frame, a container carried by said second frame, means carried on said first frame to hold said container in a predetermined position in said second frame, and means carried on said uprights for operating said holding means to release said second frame from said first frame and allow said container to tilt sideways to dump the material contained therein.

10 16. In an elevator, the combination with a base frame having a set of uprights immovable thereon, of other uprights arranged in a plurality of different sets in telescopic relation with each other and with the uprights 15 on the base frame, a distributing means mounted on the uppermost set of uprights to move therewith, a frame mounted to slide on the uprights of the base frame and also on the uprights telescoping with the base 20 frame and with each other, and a container mounted to move on the frame to discharge the contents thereof to the distributing means.

17. An elevator comprising a portable 25 base, a pair of uprights rising from the base, an open frame connecting the uprights, connected uprights guided on the first named uprights, connected uprights guided on the second named uprights, a frame 30 mounted to travel on all of said uprights through said open frame, and a container movably mounted on said last mentioned frame.

18. An elevator comprising a base having a set of uprights immovable thereon, a second set of uprights adjustable on said base uprights, means for securing said second set of uprights in different adjusted positions on the base uprights, a third set of uprights adjustable on the second set of uprights, 35 means for securing the third set of uprights in different adjusted positions on the second set of uprights, means for elevating the adjustable uprights, said means being connectible at will with the second set of uprights 40 or the third set of uprights, a frame movable to travel on all of such uprights, and a container movably mounted on said frame.

19. An elevator comprising a base, a set of uprights immovable on the base, a second set of uprights vertically adjustable on the base uprights, means for securing a second set of uprights in different adjusted positions on the base uprights, a third set of uprights adjustable on the second set of uprights, 50 means for securing the third set of uprights in different adjusted positions on the second set of uprights, an elevating mechanism embodying two cables, means for securing said two cables to the second set of 55 uprights or the third set of uprights at will, a frame movable on all of the uprights, and a container movably mounted on the frame.

In testimony whereof I affix my signature.

GEORGE A. HILLER.
